UNITED STATES PATENT OFFICE.

CHARLES T. BOONE, OF KANSAS CITY, MISSOURI.

PLANT-STAND.

1,137,737.

Specification of Letters Patent.

Patented May 4, 1915.

Application filed March 27, 1914. Serial No. 827,695.

To all whom it may concern:

Be it known that I, CHARLES T. BOONE, a citizen of the United States of America, residing at Kansas City, in the county of 5 Jackson and State of Missouri, have invented certain new and useful Improvements in Plant-Stands; and I do hereby declare that the following is a full, clear, and exact description of the invention, such as will enable others to make and use the same, reference being had to the accompanying drawings, forming a part of this specification.

The objects of my invention are: First, a stand for supporting plants or other movable objects, which may be extended to accommodate an increased number thereof; second, a knock-down, portable stand for plants, the parts of which are adapted to be detached and arranged within a small compass; third, a hoist for extensible frames in plant stands; and fourth, bases for extension plant stands, in which the floor is in sectional interchangeable parts.

The invention consists in the novel construction and combination of parts, such as will be first fully described and then specifically pointed out in the claims.

In the drawings: Figure 1. is an isometric front view of the novel plant stand, in readiness for use and prior to being extended. Fig. 2. is a view of the stand, similar to that seen in Fig. 1, and showing the parts extended in position. Fig. 3. is a vertical, sectional view of the stand, as seen extended 35 in position in Fig. 2, and taken upon the line α , α , in Fig. 4. Fig. 4. is a plan view, in detail, of the extensible base frame, and the hollow post or standard, with the top or cap plate removed, showing in dotted lines, 40 the extended position of the frame. Fig. 5. is a view, in perspective, of the base frame, and the hollow post, taken from a position in rear of the post, showing the recess for the hoisting ropes, and the hinged door 45 closing the recess in an open position, the frame being shown in a closed position. Fig. 6. is a detail view, in perspective, of the detachable hub plates supporting the hollow post, and the inner ends of the radial 50 bars of the base frame. Fig. 7. is a detail view of the cap plate, connected with the rack bar on the hollow post, in an inverted position, to show the pivoted hinges sup-

porting the adjustable shelf-supporting frame. Fig. 8. is a detail view, in perspective, of one of the extension bars of the shelf-supporting frame, broken away at one of the ends. Fig. 9. is a detail rear view of the hollow post, carrying the rack, as seen, in Fig. 5, with the door removed 60 showing the hoisting ropes connected with the rack bar, the outer vertical plate being broken away, to show the openings in the plate, for the passage of the rack-bar operating ropes. Fig. 10. is a detail side view 65 of the central, separable hinged portions of one of the shelves for the plants.

Similar numerals of reference indicate corresponding parts in all the figures of the drawing.

The main portions of the novel plant stand, as seen in the drawings, and to which reference is now made, consists of an extension base frame 12, an extension shelf-supporting frame 14, and hoisting mechanism 75 15, for the former frame 12, operable in the extension of the latter frame 15. The base frame 12 consists of a hub section 16, composed of an upper semi-circular member or plate 17, and a low semi-circular plate or 80 member 18, of the same dimensions, which are spaced apart horizontally, one above the other, the plate 18 being movably supported upon the casters 19, secured to the lower surface thereof. In the rear, straight surfaces 85 of the hub plates 17 and 18, are wide notches 20, of equal depth, for the purpose further explained. Between the plates 17 and 18, of the hub member 16, are extended the inner ends of the radial supporting bars 21, 90 which as seen in Figs. 4, 5 and 6 are four in number, the said ends being spaced apart at equal distances from each other, and arranged in position a short distance inwardly 95 from the curved line of the inner portions of the plates 17 and 18, and are secured pivotally in position by means of the bolts 22, which extend in a vertical direction through both plates 17 and 18 and the inner ends of the bars 21, said bolts having their heads 23 100 flush with the upper surface of the plate 17, the lower ends of the bolts being screw-threaded at 24, and provided with the nuts 25, which bear against the lower surface of the plate 18.

The outer end portions of the bars 21 ex-

tend outwardly a considerable distance, and are fitted within the open ends of the extension boxes 26, which are as shown, each of which consists of longitudinal side plates 27, of the requisite length, and of the proper distance apart to permit of the free telescopic movement of the bars 21 between them, and a bottom plate 28, and an outer end plate 29. In the side plates 27, of the boxes 26, are longitudinal openings 30, and in the bars 21 are secured the guide pins 31, which extend through said openings 30, and serve to retain the said bars in their proper positions within the boxes 26. To the lower 15 surfaces and outer and inner ends of the bottom plates 28, of the extension boxes 26, are secured the blocks 32^x, and the casters 32.

Brace bars 33, pivoted together at 34, are secured at 35 pivotally to the outer end portions 20 and lower surfaces of the bottom plates 28, of the adjacent outermost extension boxes 26, and serve to limit the movement of said boxes from each other. To the inner surfaces of the two innermost extension boxes 25 26 are connected rigidly the inner ends of the adjusting bars 36 and 37. Upon the bar 36 is fixed a loop 38, in which the outer end of the bar 37 is adapted to slide.

Upon the upper surface of the hub plate 30 17, and secured thereto by the screws 17^x, is mounted the lower end of a hollow post 40, which as shown is square in cross section, the box being formed to cover the central portion of the upper surface of said plate 17. 35 The inner surfaces of the side plates 41, of the box 40, are placed in a vertical plane with the parallel sides of the notch 20, and the inner portions of said plates extend inwardly to the line of the curved surface of plate 17. Between the inner surfaces of plates 41, is secured the inner vertical box plate 42. The outer, vertical plate 43, of the box 40, is arranged a short distance inwardly from the lines of the vertical outer 45 surfaces of the sides 41, so as to provide a recess 44, between the outer surface of plate 43 and the adjacent surfaces of the plates 41. This recess 44 is covered by a door 45, composed, as seen, of an outwardly-curved plate, 50 hinged at 45^x, to the outer surface of one side plate 41. Between the inner surfaces of the side plates 41 and the inner and outer end plates 42 and 43, respectively, is formed a vertical opening 46, within which is fitted 55 to move easily a sliding bar 47, of the requisite length, upon the surface of which bar, in the direction of the inner surface of plate 43, is a toothed rack 48, extending the length of the bar, the teeth being narrow in width. 60 In the plate 43, at a point a short distance downwardly from the line of the upper end of post 40, is an opening 49, in which is pivoted a gear wheel 50, the teeth of which extend to and mesh in the teeth of the rack 48.

The purpose of the gear wheel 50 is to guide 65 the rack bar 47 in its vertical movements and to keep the space in rear of the rack bar below the gear wheel clear for the entry of the hoisting ropes. This rack 47 forms a part of the hoisting mechanism for the shelf-supporting frame 16, which consists of a cap plate or shelf 51, which as shown is semi-circular in form, to the lower surface of which is secured rigidly a flat plate 52, of the same form as the plate 51, but smaller 70 in size. The plates 51 and 52 are secured rigidly to the upper end of the rack bar 47, in any convenient manner, a screw 53 being shown for that purpose.

The shelf-supporting frame 14 consists of 80 the upper bars 54, which as shown are three in number. To the lower surface and upper ends of each bar is connected one leaf of a strap hinge 55 (see Fig. 7), the other leaf being pivotally connected at 56, with the 85 lower surface of the plate 52, on the rack bar 47. One of the hinges is secured to the plate upon a line transverse to the longitudinal axis of the bar 47, the other hinges being secured at equal distances therefrom and upon 90 a line concentric with the curved surface of the plate 52.

The longitudinal surface of the bars 54 are beveled at 54° (see Fig. 8). The lower portions of the shelf-supporting frame 95 consists of extension members or boxes 56, which are provided with longitudinal grooves 57, extending through their upper surfaces and upper ends of the bars. The rear and inner surface of the grooves 57 permits the attachment of shelf supports when the bars 54 are extended as further described. The lateral surfaces of the grooves 57 are provided with V-shaped grooves 58, within which grooves are extended telescopically 100 the outer end portions of the bars 54, which are of the proper length for extension within the boxes 56. The lower ends of the extension boxes 56 are cut away at 59, upon 105 a line horizontal with the upper surfaces of 110 the extension boxes 26, of the base frame.

The hoisting devices for the rack bar 47 consist of the separate hoisting ropes 60, 61 and 62. The inner ends of these ropes are inserted within the respective openings 60^x, 115 61^x, 62^x, in the lower end of the rack bar 47, and made fast to said end. (see Fig. 9). From thence, the outer ends of said ropes pass upwardly between the inner surface of the rack bar and the vertical plate 43, of 120 post 40. The outer end of the rope 60 passes in line with the rack teeth 48, through an opening 63, in the plate 43, a short distance below the opening 49, for the rack bar guiding gear wheel 50, in which opening 63 is a 125 guide roller 64. From thence, said rope extends downwardly within the recess 44, in the post 40, thence past the notches 20, thence

over a guide roller 65, secured to the lower surface of the hub plate 18, thence extended outwardly and secured to a pin 66, on the lower surface of the adjusting bar 36, for the innermost extension boxes or members 26, of the base frame (see Fig. 3). The outer ends of the ropes 61 and 62 extend upwardly on opposite sides of the rack 48, thence through separate openings 67 and 68, in the plate 48, which are located a short distance below the position of the opening 63, thence over the guide rollers 69, in said openings. From said rollers, the said ropes extend downwardly within the recess 44, thence 15 over guide rollers 70, on the lower surface of the hub plate 17, within the notch 20, thence extended forwardly and connected with the pins 71, on the inner end portions of the two adjacent inner extension boxes 26, of 20 the base frame. The floor for the base frame is composed of separate segment boards, and with the exception of the two outer ones, removable when the parts of the stand are extended.

25 As seen in Fig. 1, the outer segment boards 72 and 73 are fixedly connected by screws 73°, with the upper surfaces of the respective outer extension boxes 26, of the base frame. The inner end of the segment 30 boards are curved inwardly at 72^x, and 73^x, and fit snugly against the curved surface of the hub plate 17, upon the upper surface of which plate are secured the inner ends of the outwardly-extended guide plates 74. The 35 removable members or boards of the floor consist of the triangular shaped boards 75 and 76, which are adjacent the inner surfaces of the respective fixed boards 72 and 73, and terminate at a point, these boards 40 being provided with dowel pins 77, which enter openings therefor in the boards 72 and 73. The next floor members 78 and 79, which are adjacent the respective boards 75 and 76, are increased in width, and also 45 abut at their inner, curved ends, with the hub plate 17. Between these boards 78 and 79 is the intermediate board 80, of increased width to that of either board 78 or 79, these boards 78, 79 and 80, having dowel pins on 50 their radial surfaces, and joined together, as described of boards 72 and 73.

Upon the lower ends of the extension boxes 56, of the shelf frame, which are extended toward the respective boards 72 and 73, are connected the hinges 81, one leaf of each of the hinges being secured to the said end of the boxes, and the other leaf secured to the upper surfaces and outer end portions of the fixed boards 72 and 73, respectively.

55 Upon the lower end portion and side of the intermediate extension box 56 is secured a bolt 82, the outer end of the bolt extending within a bolt opening 83, in the outer end portion of the board 80. The shelf supports

are mainly supported by the bars 54, and, as seen, are formed from short lengths of wire, bent at right angles, to form the horizontal rests 85, and risers 86, the latter being long or short, in proportion to the number of shelf rests required. As arranged, the inner ends of the upper shelf rests are secured within openings in the bars 54, at a point a considerable distance downwardly from the upper ends of said bars, and the risers for the lower shelf support secured within the 75 openings 86^x, these supports being in series, and the risers on each bar 54 being the same in height.

Upon the horizontal shelf supports 85 are laid the shelves 88. These shelves are 80 formed in the arcs of circles, and vary in length, the lower shelf obviously being the greatest in length. The shelves are formed in two sections 89 and 90, separated transversely, at a point intermediate the ends of 85 the shelves, and said parts connected together by hinges 91 (see Fig. 10), and over the joints extend the joint-closing plates 91^x.

The plant stand constructed as heretofore described, and as seen in Fig. 1, may now be 90 employed for the uses designed, the floor affording as large an area for the plants as the shelves, and furthermore, the closeness of the joints of the floor-sections prevent the loose soil from being scattered, and upon 95 which plants may be exchanged and moistened.

When an increase in the size of the stand is desired, the floor members 75, 76, 78, 79 and 80 are removed from each other and the 100 base frame, the bolt 82, on the extension box 56, being first removed from the opening 83, in the floor member 80. Sufficient power is now applied to the extension boxes 26, of the base frame, and said boxes drawn outwardly 105 to their full extent, at the same time drawing upon the ropes 60, 61 and 62, and hoisting the rack bar 47, which, in moving upwardly with the cap plates 51 and 52, draw upon the bars 54, and drawing said bars 110 from the extension boxes 56 the full height required. In place of the intermediate floor member 80, I now employ (as seen in Fig. 2) a like floor member 92, which is of increased length to that of the floor member 80, upon 115 the lower surface of which is a block 93, which block, when the rack is in an elevated position as seen in Figs. 2 and 3, comes into contact with the inner, adjusting bar 36, and locks the parts in their outwardly-extended positions. It will now be seen that space in the groove 57 in the extension box 56, below the lower ends of the bars 54,

afford space for the attachment of another shelf support 94, independent of the shelf support 85, as seen at 94, affording supports for an additional shelf 95. The extensions of the bars 54 also afford means for adding

thereto, at their upper ends, like shelf supports, and thereby add to the efficiency and plant-supporting capacity of the plant stand. In place of the floor members 75, 76, 5 as in Fig. 1, the floor members 96 and 97, as seen in Fig. 2, are employed, the inner ends of which board are provided with outwardly-curved extensions 98, which fit against the curved hub plate 17, beneath the 10 retaining bars 74, and in the space formed by the outward movement of the floor members 72 and 73, which move outwardly with the extension boxes 26, of the base frame.

In place of the floor members 78 and 79, 15 in Fig. 1, floor members 99 and 100, of increased lengths, are employed, as seen in Fig. 2, the increase in length of these substituted members being also accompanied with an increase in width, in proportion to the 20 extension of the parts of the stand, as before described.

It is obvious that the invention is applicable to a stand in which the base frame may form a complete circle, if desired, the purpose 25 being to not only afford means for increasing the supporting capacity of the stand, but to make a portable stand, the parts of which may be separated and quickly put together, and accommodate itself to the space allowed 30 for display purposes.

The invention is adapted to the display of goods in store windows, and other uses, such as fruit drying, in which the stand may be given any extended height requisite for the 35 purpose.

Such modifications of the invention may be employed as are within the scope of the appended claims.

Having fully described my invention, 40 what I now claim as new and desire to secure by Letters Patent is:

1. In a plant stand a base frame composed of horizontal pivoted extensible members extending radially from said base frame, and 45 folding connecting devices connected with adjacent extensible members.

2. In a plant stand a base frame comprising a hub, and horizontal extensible members pivotally connected with said hub and 50 extending radially therefrom, and adjustable folding devices connected with adjacent extensible members.

3. In a plant stand, a base frame composed of upper and lower horizontal hub 55 members, radial supporting bars extending between said hub members, and pivotally connected therewith, extensible members connected with said bars and folding devices connected with said extensible members.

4. In a stand for displaying movable objects, the combination with a suitable base 60 of an upwardly extended shelf support, having a longitudinal groove extending a certain depth in face portion, and an extensible

member telescopically fitted within said 65 groove, said groove being adapted to receive a shelf support upon the outward extension of said extensible member.

5. A plant stand composed of a hub member, and a base frame composed of radial 70 bars pivotally connected with the hub member, and extensible members on said bars, an upright post connected with the hub member, and an extensible member upon 75 said post, and hoisting devices on said post for hoisting the said extensible member and controlled by the extension of the extensible members on the radial bars of the base frame.

6. A stand for displaying movable objects, 80 comprising a base frame, composed of a hub member, and radial members having telescopic extensible parts, an upright hollow post carried by the hub member, and a sliding bar, and hoisting ropes connected with 85 the sliding bar and also connected with the extensible parts of the base frame.

7. A stand for displaying movable objects, comprising a base frame composed of a hub member, and radial bars connected pivotally 90 with the hub member, and extensible members carried by said bars, an upright hollow post carried by said hub member, a sliding bar within the said post, a shelf-supporting frame having extensible parts connected 95 with the sliding bar, and hoisting ropes connected with the sliding bar and also connected with the extension members of the base frame.

8. A stand for displaying movable objects, 100 comprising a base frame having a hub, and radial extension members connected with the hub, an upright hollow post, a sliding bar within the post, and hoisting ropes connected with the sliding bar and the extension 105 members of the base frame, and a floor member on the base frame having means thereon to secure the said extension parts of the base frame when in an extended position.

9. A stand for displaying movable objects, 110 comprising a base frame having a hub member, and radial extension members connected with the hub, and an upright hollow post supported by said hub member, a sliding bar within said post, and hoisting ropes connected with the sliding bar and also with the 115 extension members of the base frame, and a floor member for the base member having means thereon for engaging with the bar adjusting devices on the extension members 120 thereof.

10. In a display stand, the combination with a base frame, composed of upper and lower hub members, of a series of radial bars pivotally connected at their inner ends with the said hub members, extension boxes connected with said bars, a hollow post connected with the upper hub member, and a

sliding bar within said post, adjusting bars connected with adjacent intermediate extension boxes, and a series of bar-hoisting ropes connected at their inner ends with the lower end of said sliding bar, the outer end of one rope being connected with one of said adjusting bars, and the outer ends of the

other ropes with the inner ends of the respective adjacent extension boxes.

CHARLES T. BOONE.
